UNITED STATES PATENT OFFICE.

ALLEN ROGERS, OF BROOKLYN, NEW YORK, ASSIGNOR TO CHARLES T. DAVIS, OF BROOKLYN, NEW YORK.

ANTISEPTIC AND GERMICIDAL TABLET.

1,276,119.

Specification of Letters Patent. Patented Aug. 20, 1918.

No Drawing.

Application filed April 2, 1918. Serial No. 226,161.

To all whom it may concern:

Be it known that I, ALLEN ROGERS, Ph. D., a citizen of the United States, residing at Brooklyn, in the county of Kings and State 5 of New York, have invented new and useful Improvements in Antiseptic and Germicidal Tablets, of which the following is a specification.

This invention relates to improvements in 10 antiseptic and germicidal tablets, pertaining more particularly to tablets characterized by great germicidal potency and low toxicity.

Heretofore tablets for these purposes 15 have generally been of the type known as bi-chlorid of mercury. While tablets of this type have been universally used satisfactorily, it has been found that a double salt of the potassium mercuric iodid type 20 (having the formula $2\text{HgI}_2\cdot2\text{KJ}\cdot3\text{H}_2\text{O}$) possesses higher antiseptic and germicidal value than the commercial bi-chlorid of mercury tablet, producing a more favorable 25 action in use by reason of the fact that the mercuric element is not precipitated by the albumen of the blood or serum, and is far more efficient in its action than other compounds used for the same purpose. The value of a prepared solution of this double 30 salt as a germicide has been demonstrated by its use—under the trade name of kalmerid—as a storage fluid for sutures as indicated in the patent to Watson dated

Oct. 31, 1916, No. 1,202,931. While this 35 double salt is valuable for antiseptic and germicidal purposes, its use has, heretofore, been limited mainly to the use disclosed in the Watson patent, due to the fact that the double salt as such has certain characteristics 40 which normally affect its use in other relations. For instance, it has the disadvantage of being unstable when dissolved in water, due to the more or less precipitation of the mercury salt. Another characteristic 45 is its deliquescent action when exposed to air. Both of these characteristics are such as to prevent its use in tablet form as a substitute for the bi-chlorid of mercury tablet, since the characteristic of deliquescence would tend to prevent its being utilized 50 in tablet form as a stock in trade, and if used in the broken down condition, would provide a solution different from that which is desired.

55 I have found, however, by experiment,

that this double salt can be utilized for this purpose when the double salt has been subjected to the action of a stabilizing or an oxidizing agent which so affects the double salt as to prevent the reduction of the mercury to the mercurous condition, then combining with the treated double salt a binder or agent, innocuous to materially affect the solution, but which acts to prevent the deliquescent effect.

In practice, I have used potassium iodid as the stabilizing agent, adding a small excess of this salt to the potassium mercuric iodid to form a mixture therewith, a sufficient quantity being added to prevent reduction in solution to insoluble mercuric iodid. The invention is not limited, however, to this, since other salts may be employed for the purpose, such for instance as ammonium nitrate, potassium chlorate, etc., 70 these stabilizing or oxidizing salts so employed having the characteristic of being able to practically prevent the normal chemical reduction which is provided upon introducing potassium mercuric iodid into 75 water, viz: breaking down the mercurous salt content by the potassium iodid content into mercuric iodid and metallic mercury. The introduction of the oxidizing agent prevents this reduction and thereby produces 80 the desired solution, the potassium mercuric iodid thus remaining stable in its solution form.

The preferred binder for preventing the deliquescent action of the double salt is sodium chlorid—table salt—which prevents the deliquescent action when combined with the double salt referred to. I prefer to employ this binder not only because of its ability to prevent deliquescence and thus 90 enable the double salt to be placed in tablet form, but, in addition, because this sodium chlorid content of the solution, by reason of its saline content, closely approximates the physiological saline constituency of the 95 blood and serum, so that when the germicidal or antiseptic solution is introduced into a wound, the astringent action which is generally common to many antiseptic solutions is prevented, the solution produced 100 by the tablet of the present invention being of a bland and non-irritating character.

The invention however is not limited to the use of the sodium chlorid as the binder, since ammonium chlorid, sodium bi-carbonate, dex- 110

trin, and several other inorganic and organic compounds will give somewhat similar results and therefore serve as equivalents for the sodium chlorid. In other words, the general controlling characteristics of the binder are the ability to prevent deliquescence of the double salt while in tablet form, the solubility of the binder in order to produce the solution, and its substantially innocuous relation to the double salt; as an additional characteristic which may or may not be present, the binder may be non-astringent.

In producing the tablet, the proportions of binder may vary, a preferred proportion—where the binder is in the form of sodium chlorid—is: kalmerid, 10 parts, potassium iodid, 1 part, and sodium chlorid, 39 parts, these proportions seeming to give the best results. However, I have used smaller quantities of the binder as well as larger quantities without harmful effect upon the working quality of the tablet, the smaller quantity making a tablet slightly smaller than the average antiseptic tablet, while larger quantities make an excessively large tablet, but with no material advantage, so that the particular proportions named, are more or less approximate, and the variations therefrom are considered as within the scope 30 of the invention.

In addition, it is desirable that tablets of this exceedingly poisonous type should have distinguishing characteristics which would act more or less in the nature of an indicator 35 or signal. This for the reason that it is desirable that the tablets themselves indicate the dangerous character of the contents, and that when in solution form, a distinguishing characteristic is presented which will 40 indicate the dangerous character of the solution as well as indicating to the intentional user that the prepared solution has been produced by the proper tablets. For this purpose I prefer to employ a very small quantity 45 of some coloring substance, that preferred being a violet coloring substance, although I have used tourquine blue as well as other colors. However, the violet coloring substance gives a color which is characteristic 50 and which imparts a distinct blue cast to the solution. The advantage of the color in the tablet is that it serves to draw the attention of the user to its presence in the tablet, while in solution it serves as a danger signal to the operator or to any person 55 who might see such a colored solution in a containing vessel.

In use, the amount of coloring substance employed is comparatively small. For in-

stance in the quantitative statement above 60 made, the coloring substance would be about .5 part.

From the above it will be understood that I am thus able to produce a tablet for this purpose in which the germicide employed 65 is far superior to those heretofore employed for the purpose, overcoming the difficulties which have heretofore been present in its use by solving the problems of substantially eliminating deliquescence and rendering it stable when employed in the formation of a solution.

While I have herein set forth various ways in which the invention may be produced, it will be readily understood that the binder 75 and the oxidizing or stabilizing agent may be of different forms, and the relative proportions of parts employed may vary to meet the individual uses to which the tablet is to be put, and I desire it to be understood that I reserve the right to make any and all of such changes and modifications, as well as a substitution of equivalents, insofar as the same may fall within the spirit and scope of the invention as expressed in 85 the accompanying claims when broadly construed.

What I claim is:

1. An antiseptic tablet of potassium mercuric iodid containing a stabilizing agent in 90 quantity sufficient to prevent reduction in solution to insoluble mercuric iodid and a suitable binder acting as a filler and serving to prevent deliquescence of the tablet.

2. An antiseptic tablet of potassium mercuric iodid containing a stabilizing agent in quantity sufficient to prevent reduction in solution to insoluble mercuric iodid, and a binder of sodium chlorid, the latter being present in an amount to give to the antiseptic 100 solution of normal strength a tonicity approximating that of the blood.

3. An antiseptic tablet of potassium mercuric iodid containing a stabilizing agent of iodid salt in quantity sufficient to prevent 105 reduction in solution to insoluble mercuric iodid, and a salt preventing deliquescence acting as a binder and present in an amount to give to the antiseptic solution of normal strength a tonicity approximating that of 110 the blood.

In testimony whereof I have hereunto set my hand in presence of two subscribing witnesses.

ALLEN ROGERS.
